UNITED STATES PATENT OFFICE.

DWIGHT A. HITCHCOCK, OF DETROIT, MICHIGAN, ASSIGNOR TO THE MONARCH COUPLER COMPANY, LTD., OF DETROIT, MICHIGAN.

DRAFT-RIGGING.

No. 884,585.

Specification of Letters Patent. Patented April 14, 1908.

Application filed July 30, 1904. Serial No. 218,827.

To all whom it may concern:

Be it known that I, DWIGHT A. HITCHCOCK, residing at Detroit, in the county of Wayne and State of Michigan, a citizen of the United States, have invented certain new and useful Improvements in Draft-Rigging, of which the following is a specification, reference being had therein to the accompanying drawings.

10 The invention relates to new and useful improvements in draft rigging, and consists in the construction, arrangement and combination of the various parts, as more fully hereinafter described, and particularly pointed out in the claims.

15 In the drawings, Figure 1 is a vertical, central longitudinal section through the draft rigging, embodying my invention. Fig. 2 is a top plan view thereof, with the yoke broken away. Figs. 3 and 4 are elevations of two follower members illustrating the construction of their inter-engaging faces. Fig. 5 is a 20 section of one end of the draft rigging, similar to Fig. 1, showing slightly modified form of inter-engaging faces of the rotatable and non-rotatable members, and, Figs. 6 and 7 are perspective views, illustrating the construction of these inter-engaging, friction-producing faces, shown in Fig. 5.

25 30 My draft rigging belongs to that type, in which followers have inter-locking spiral bearings, so as to produce a rotational movement thereof, upon non-rotatable members of the followers. I have not shown in detail the side plates and other parts of the draft rigging, as they may be of any usual construction, but have simply indicated in Fig. 2, the usual location of the lugs or stops on the side plates.

35 40 A represents the draft bar, B the yoke. C, C' are two spiral springs concentrically arranged between the two followers, D, D'. These followers D, D' have formed on them, the inwardly extending sleeves E, E', provided with inter-locking spirals F, F', so as to 45 produce a rotational movement of the followers when the spring is compressed from either end, and the return of the followers to their normal position as the spring expands. The 50 particular manner of forming this spiral inter-locking feature is immaterial, as it may be done in any desired way.

55 G is the head of the draft bar. At each end of the yoke and outside of the followers,

D, D' are non-rotatable followers, II, II'. I have shown these followers as made up of two parts, a and b, these parts engaging lugs, i. e. in the construction shown, I have illustrated the parts a as having sockets or recesses c and the parts b having corresponding lugs d engaging therewith. The parts a may be of simple malleable iron, while the parts b are preferably of steel, so as to resist the wear that it is to have in use.

60 Between the follower members, D, D' and II, i. e., between the rotatable and non-rotatable members of the followers, I provide means to increase the friction. This means preferably consists of inter-engaging projections or recesses in the complementary parts. 70 In Figs. 1, 2, 3 and 4, I have shown this increased friction as produced by providing on the members D, D', the annular V-shaped ribs I, which engage corresponding V-shaped grooves J in the members b of the followers 75 H. Suitable provision is made for the wearing of the parts, as illustrated in Fig. 1. In Figs. 5, 6 and 7, I have shown this increased frictional resistance as produced by a series of complementary inter-locking spiral lugs or 80 teeth K, K'.

85 It is obvious to any one familiar with the construction of such draft rigging, that as the springs are compressed by the movement of the yoke in either direction, the inter-locking spiral sleeves E, E' will cause a rotational movement of the followers D, D' and this rotational movement will produce increased frictional resistance to the compression of the springs, due to the rotation of these two 90 members and this frictional resistance will be largely increased by the engagement of the V-shaped ribs I in the V-shaped grooves J or by the engagement of the spiral lugs or teeth K, K', shown in Figs. 5, 6 and 7.

95 100 I have shown members b as provided with inwardly projecting sleeves L, which pass through the central aperture in the followers D, D'. These sleeves form guides and supports for the springs C'. What I claim as my invention is:—

1. In a draft rigging, the combination with a yoke, followers composed of a non-rotating and a rotating member, sleeves on the non-rotating members projecting through apertures in the rotating members and springs between the followers about the sleeves. 105
2. In a draft rigging, a follower composed

- of a rotary member and a non-rotary member, a V-shaped rib on one member and a complementary V-shaped groove on the other, for the purpose described.
5. 3. A strain-resisting mechanism, comprising a conical wedge member, a relatively rotatable member coöperating therewith, and an elastic resistance medium, substantially as described.
- 10 4. A strain-resisting mechanism, comprising a pair of relatively rotatable members adapted during the action of the mechanism to have wedge engagement with each other, one of said members being of conical form, whereby friction is produced to resist

strains applied to the mechanism, substantially as described.

5. A strain-resisting mechanism, comprising a rotatable conical wedge member and a coöperating member frictionally engaged thereby, said wedge member being rotatable in a direction at right angles to its axis, substantially as described. 20

In testimony whereof I affix my signature in presence of two witnesses.

DWIGHT A. HITCHCOCK.
